(57) **CLAIM**

The ornamental design of a globe for a suspended luminaire, as shown and described.

DESCRIPTION

FIG. 1 is a perspective view of a first embodiment of a luminaire showing our new design;

FIG. 2 is a side elevational view thereof;

FIG. 3 is a bottom view thereof;

FIG. 4 is a top plan view thereof;

FIG. 5 is a perspective view of a second embodiment of a luminaire of the new design;

FIG. 6 is a side elevational view thereof;

FIG. 7 is a bottom view thereof; and,

FIG. 8 is a top plan view thereof.

The broken line environmental showing is for illustrative purposes only and forms no part of the claimed design.
